UNITED STATES PATENT OFFICE.

ISAAC N. HAMILTON, OF READING, PENNSYLVANIA, ASSIGNOR TO CARPENTER STEEL COMPANY, OF READING, PENNSYLVANIA, A CORPORATION.

PROJECTILE.

SPECIFICATION forming part of Letters Patent No. 740,977, dated October 6, 1903.

Application filed September 15, 1902. Serial No. 123,458. (No model.)

To all whom it may concern:

Be it known that I, ISAAC N. HAMILTON, a citizen of the United States of America, and a resident of Reading, in the county of Berks and State of Pennsylvania, have invented certain new and useful Improvements in Projectiles, of which the following is a specification.

My invention relates particularly to that class of armor-piercing projectiles in which a separately-formed head portion is united with a main body or shell portion; and it has for one of its most important objects the provision of a projectile of the type stated wherein the bursting of the body or shell of the projectile is assured when the explosion of the bursting charge takes place when the projectile is outside the gun and will be expelled when the exposure of the bursting charge takes place prematurely—that is to say, when the shell is in the gun and its body is reinforced by the wall thereof—whereby the efficiency of the bursting shells is secured and at the same time the liability of the destruction of guns thereby when the explosion is premature is avoided.

To this end the invention consists, broadly, in a projectile having a main body or shell and a separately-formed head portion so secured together that the resistance to explosion of the head portion is greater than the resistance to rupture of the shell when said shell or body of the projectile is not reinforced by the wall of the gun.

The object hereinabove named as well as other objects and advantages which are set forth in the following description of the invention are attained by the construction illustrated in the accompanying drawing.

The drawing is a longitudinal section of a projectile embodying my improvements in preferred form.

The main body or shell *a* of the projectile is cylindrical in form, and the central opening therethrough is closed at its front end by the separately-formed head portion *b*, having a shank *c* rigidly engaged therewith, and at its rear end by a closure-plug *d* screwed thereto, as usual, leaving an intermediate interior chamber *e*. The exterior of the shell *a* is provided near its rear end with the usual copper band *f* of somewhat greater exterior

diameter than the bore of the gun to engage the rifling of the latter and give rotation to the projectile, and the front end or head is of conical form, tapering to a point from the maximum diameter of the shell *a* at the burleigh *g*, which latter I preferably form by means of a rigidly-inserted copper band closely fitted exteriorly to the bore of the gun instead of grinding the hard shell material itself to the desired diameter, as usual, thereby insuring axial alinement, while avoiding undue wear and tear upon the bore of the gun.

The practical impossibility of securing solid and homogeneous metal at the heart of a solid forging, such as a projectile of large or even medium size, owing to "piping" and "segregation," is well known, and the superior quality of hollow forgings, especially when "hollow-forged," is recognized. In the manufacture of projectiles it is also desirable that the quality or character of the metal employed in its construction should be varied to correspond with the different character of strains to which it is subjected at the head and body, respectively. Thus the formation of the head separately from the body of the projectile and of a special quality of steel offers decided advantages, provided the union of the parts be effected in such a manner as to satisfactorily meet the requirements, which it is my object to accomplish.

The weight of metal employed in a projectile is most effectively distributed when the rear body portion, which is not subjected to the great radial compression strains due to impact and penetration, is left hollow, and, moreover, the interior chamber *e* thus formed may be utilized for the storage of a bursting charge when desired. In my improved construction I therefore extend the shank *c* of the separately-formed head portion *b* into the hollow shell *a* only a sufficient distance to give solidity to the forward portion of the shell *a* and to insure a rigid connection therewith, the latter being attained, as shown, by not only providing a tight fit between the parts, but by also slightly flaring outwardly, as may be required, the recessed inner end of the inserted shank *c* into the slightly-enlarged bore, as indicated at *l*.

The conical head or "ogive," which ex-

tends from the point to the burleigh *g*, is formed, as shown, partly by the separately-formed head portion *b*, which is provided with a circular shoulder *h*, and partly by the forward end of the shell *a*, which is somewhat reduced in exterior diameter outwardly from the burleigh *g* to its end face *i*, against which the shoulder *h* of the separately-formed head portion *b* abuts when forced home in the shell, a buffer ring or washer *j*, herein-after referred to, being preferably interposed.

The inner end of the inserted shank *c* is recessed, as indicated at *k*, so as to form an extension of the chamber *e* into said shank and at the same time provide the latter with a circular wall of comparatively thin metal at its recessed end to permit of flaring, as already described. This recessed formation of the shank end gives a degree of elasticity to the latter which either without the previous flaring described or with it, as is required in other cases, will insure the bursting of the shell when a normal explosion of a bursting charge placed in the chamber *e* takes place. 25 If, however, such explosion should take place prematurely while the projectile is still in the gun, the shell *a* being then reinforced by contact with the walls of the latter sufficiently to make the expulsion of the inserted shank 30 the easiest vent, such expulsion will take place, thus providing a safety-valve whereby injury to the gun will be avoided.

The conical head or ogive of the projectile in my improved construction is formed partly only, as already described, by the separately-formed head portion *b*, the forward portion 35 of the shell *a* forming the part of largest diameter, extending from the shoulder *i* to the burleigh. This construction not only 40 enables me to provide a sufficient length of shank *c* within the shell without restricting the chamber *e*, while at the same time providing a sufficient head portion of the special-quality steel required to insure penetration, 45 the main effect of which is accomplished before the slightly-tapered end of the shell *a*, supported by the inserted shank *c*, comes in contact with the partially-pierced plate. The buffer-ring *j*, interposed, as shown, between 50 the shouldered head portion *b* and the end face *i* of the shell, serves in the first place to slightly cushion the head portion *b* and reduce the liability of breakage and after being crushed by the force of impact and spreading 55 in diameter beyond the normal serves as

a lubricant for the entering shell portion *a* of the projectile, thereby reducing the destructive action upon the latter. Thus the effect of my improvement is to produce a composite projectile not only free from the internal weakness inherent in the integral formation, but insuring greater penetration and safety. 60

What I claim is—

1. A projectile comprising a cylindrical 65 body or shell having a longitudinal bore with a widened portion intermediate its ends, a closing means for the rear end of said bore, and a separately-formed head portion having a shank entering the forward end of said bore and closing the same, said shank having its rear end located in the widened portion of the bore, and recessed and elastic, said parts being so related as to provide within the shell a chamber for a bursting charge 70 of which chamber the recessed portion of the shank forms an extension, for the purpose specified.

2. A projectile comprising a cylindrical body or shell having a longitudinal bore with 80 a widened portion between its ends, a closing means for the rear end of said bore, and a separately-formed head portion having a shank entering the forward end of said bore and closing the same, said shank having a 85 recessed rear end with flared wall located in the widened portion of said bore, and said parts so related to each other as to provide within the body a chamber for a bursting charge of which chamber said recess forms 90 an extension.

3. A projectile, comprising a cylindrical body or shell of reduced diameter at its formed end to form a portion of the ogive or conical head, a separately-formed head portion shouldered against said reduced end of the shell and having a shank entering the latter, and a buffer-ring interposed between the shouldered parts, the relation of the parts being 95 such that said ring when crushed by the impact of the head against the object struck, will serve as a lubricant for the entering shell portion for the purpose specified.

Signed at Reading, Pennsylvania, this 8th day of September, 1902.

ISAAC N. HAMILTON.
